UNITED STATES PATENT OFFICE.

THOMAS J. JETT, OF HARRIMAN, TENNESSEE, ASSIGNOR OF ONE-HALF TO
L. TYLER DAVIS, OF SAME PLACE.

DESIGN FOR A RAILROAD-SPIKE.

SPECIFICATION forming part of Design No. 26,748, dated March 9, 1897.

Application filed November 10, 1896. Serial No. 611,682. Term of patent 7 years.

To all whom it may concern:

Be it known that I, THOMAS J. JETT, a citizen of the United States, residing at Harriman, in the county of Roane and State of Tennessee, have invented and produced a certain new and original Design for Railroad-Spikes; and I do declare the following to be a full, clear, and exact description of the invention, such as will enable others skilled in the art 10 to which it appertains to make and use the same.

My invention relates to an original design for a railroad-spike.

The design relates to the entire configuration of the spike.

My invention relates particularly to the design for a railroad-spike as illustrated in the accompanying drawings, in which—

Figure 1 is a perspective view of a railroad-spike embodying my design, and Fig. 2 is a transverse section of the same on the horizontal broken line of Fig. 1.

The leading features of my design appear in the following description.

1 25 1 represents the spike, of which 2 is the usual head and 3 the tapering quadrilateral point. The body 4 of the spike is square in cross-section, and the front side 5 is a true

plane, while the back 6 and the two sides 7 and 8 are formed with a series of projecting 30 ribs 12, 13, and 14, each one having an inclined face 15 and a curved shoulder 16. The back 6 of the spike is also formed with an additional rib 17, approximately in the same plane as the lip 18.

By referring to the vertical dotted line *a b* in Fig. 1, which is parallel with the front face 5 of the spike, it will be seen that beginning with the rib 12, which is the lowermost one, the distance between the front face 5 and the 40 ribs above the lower one gradually increases as they approach the head, the rib 13 extending a greater distance than the rib 12 and the rib 14 a greater distance than the rib 13.

Having thus fully described my railroad-spike, what I claim as new and useful, and desire to secure by Letters Patent of the United States, is—

The design for a railroad-spike, substantially as herein shown and described.

In testimony whereof I hereunto affix my signature in presence of two witnesses.

THOMAS J. JETT.
